UNITED STATES PATENT OFFICE.

HERBERT B. KISSINGER, OF LOCK HAVEN, PENNSYLVANIA.

AUTOMATIC CIRCUIT BREAKER.

1,424,921.

Specification of Letters Patent.

Patented Aug. 8, 1922.

Application filed November 27, 1920. Serial No. 426,861.

To all whom it may concern:

Be it known that I, HERBERT B. KISSINGER, a citizen of the United States, residing at Lock Haven, in the county of Clinton and State of Pennsylvania, have invented certain new and useful Improvements in an Automatic Circuit Breaker, of which the following is a specification.

The present invention relates to an automatic circuit breaker, and has for its object to provide a device of this character which embodies novel features of construction whereby it can be substituted for the ordinary Edison fuse plug which must be replaced when blown, and which can be used in connection with the ordinary Edison base.

A further object of the invention is to generally improve upon circuit breakers of this character by providing a device which will be of extremely simple, durable and inexpensive construction, one which is efficient and reliable in operation, and well adapted to the purpose for which it is designed.

With these and numerous other objects in view, this invention resides in certain novel features of construction, and the combination and arrangement of parts as will be herein-after fully described and claimed.

30 In the drawing:—

Figure 1 is a longitudinal sectional view through a circuit breaker constructed in accordance with the invention, and

Figure 2 is a section taken on the line 2—2 of Figure 1 looking downwardly.

Specifically describing the present embodiment of the invention, the numeral 1 designates the base or body of the circuit breaker which may be formed of any suitable insulating material. The end of the base is conical in shape as is usual in the ordinary fuse plug. A threaded sleeve 2 is fitted on the base 1 forming one of the contact members and being adapted to be screwed into an Edison base in the usual manner. A cylinder 3 is mounted on the annular flange 4 of the base 1 and is fixed thereto by means of bolts 5. A screw threaded plug 6 is mounted in the bottom of the base 1 and forms one of the contact members with the Edison base. This base 1 is of hollow construction and the contact spring 7 is suitably mounted on the plug 6 so as to be within the interior of the base 1. This contact spring 7 is of substantial U-shape and the legs thereof are curved so that their

lower halves will converge toward each other while their upper halves diverge from each other.

A core 8 having the plate 9 formed on its bottom end which is situated on top of the base 1 is surrounded by a solenoid 10 having the usual winding 11 thereabout. The size and amount of wire which will be used for the winding will be determined by the voltage and amperage. A cover 12 is mounted on the cylinder 3 and held in place by means of the bolts 5 and is provided with a central aperture through which is slidably mounted the plunger 13. This plunger 13 extends through the insulating core 8 down into the base 1 and is provided at its lower end with a contact knob 14 which is provided with annular groove intermediate its ends so that it may be engaged by the contact spring 7 as shown in Figure 1. A coil spring 15 is disposed around the plunger 13 within the insulating core 8 and has one end attached to the cover 12 while the other end is suitably attached to the plunger 13 and this spring will normally have a tendency to draw the plunger upwardly or out of the base 1.

The circuit between the sleeve 2 and the plug 6 is completed through one of the bolts 5, rod 16, winding 11, rod 17, plunger 13, contact knob 14, and contact spring 7. An armature 18 is provided with a central opening through which extends the plunger 13 and this armature 18 is normally held out of engagement with the solenoid 10 by means of leaf springs 19 which are attached thereto and have their outer ends fixed between the plate 9 and the top of the base 1. A stop 20 is fixed on the plunger rod 13 and will be engaged by the armature 18 so that when same is attracted by the solenoid 10 the plunger 13 will be moved so as to break the contact between the contact knob 14 and the contact spring 7.

When it is desired to again close the circuit, the operator merely pushes inwardly upon the plunger 13 until the latter has been forced into operative position and the contact spring 7 grasps the contact knob 14 by having the middle of its arms situated within the groove provided therein.

From the foregoing description, taken in connection with the accompanying drawings, the construction and operation of the circuit breaker will be readily understood without a more extended explanation. As

numerous changes in form, proportion, and in the minor details of construction, maybe resorted to without departing from the spirit of this invention, I do not wish to be limited to the construction herein shown and described other than as claimed.

Having thus described the invention, what I claim as new and desire to secure by Letters Patent is:—

- 10 1. An automatic circuit breaker including a base, a pair of contact elements on the base, a spring actuated plunger adapted to engage the contact elements to close a circuit, a solenoid surrounding the plunger, the winding 40 of said solenoid being in circuit with the plunger through one of the contact elements, a coil spring surrounding the plunger for normally holding the same out of contact with the other contact element, a contact 15 knob formed on the inner end of the plunger and having an annular groove therein, a contact spring situated on the last mentioned contact element, said spring being substantially U-shaped and having its arms curved 20 so that their mid portions will be closer to each other than their other portions whereby the mid portions may fit in the groove of the contact knob for normally holding the same in engagement with the contact spring, 25 30 an armature for the solenoid, a spring re-

sisting actuation of the armature by the solenoid, and means for moving the plunger upon movement of the armature by the solenoid.

2. An automatic circuit breaker including 35 a hollow base, a contact plug secured in the lower portion of the base a contact sleeve surrounding the base, said sleeve provided with an annular flange upon its upper end, a cover for the base, a solenoid situated with 40 in the base, an armature for the solenoid, a pair of leaf springs having one end fixed to the base and their other ends fixed to the armature for resisting actuation of the armature by the solenoid, a spring actuated 45 plunger adapted to engage the contact plug, said plunger extending through the armature and through the solenoid means electrically connecting the winding of the solenoid with the contact sleeve, means for electrically connecting the winding of the solenoid with the plunger, and means for actuating the plunger upon movements of the armature by the solenoid.

In testimony whereof I affix my signature 55 in presence of two witnesses.

HERBERT B. KISSINGER.
